GIRDLE FOR WOMEN'S APPAREL

Filed March 9, 1922

INVENTOR.
Otto David,
BY
Frantz and Richards
ATTORNEYS.

UNITED STATES PATENT OFFICE.

OTTO DAVID, OF FAR ROCKAWAY, NEW YORK.

GIRDLE FOR WOMEN'S APPAREL.

Application filed March 9, 1922. Serial No. 542,251.

To all whom it may concern:

Be it known that I, OTTO DAVID, a citizen of the United States, residing at Far Rockaway, in the county of Queens and State of New York, have invented certain new and useful Improvements in Girdles for Women's Apparel; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification.

This invention relates, generally, to improvements in girdles for women's apparel; and the invention has reference to a novel construction of girdle having terminal portions which serve both an ornamental and utilitarian function.

The invention has for its principal object to provide a novel construction of girdle for women's apparel, consisting of a flexible main body portion to encircle the waist of the wearer, and capable of being tied or knotted or otherwise secured to hold the same against displacement, the free depending ends of said main body terminating in ornamental portions provided with pockets or receptacle members in which small articles of various kinds may be conveniently carried.

Other objects of this invention, not at this time more particularly enumerated, will be clearly understood from the following detailed description of the same.

With the objects of the invention in view, the same consists, primarily, in the novel construction of girdle for women's apparel hereinafter more fully set forth; and, the invention consists, furthermore, in the novel arrangements and combinations of the various devices and parts, as well as in the details of the construction thereof, all of which will be hereinafter more fully described, and then finally embodied in the claims appended hereto.

The invention is clearly illustrated in the accompanying drawings, in which:

Figure 1 is a perspective view of a novel girdle made according to and embodying the principles of this invention, and Figure 2 is a detail fragmentary vertical longitudinal section of one of the terminal portions of the same, taken on line 2-2 in said Figure

1, and drawn on an enlarged scale. Figure 3 is a view similar to that shown in Figure 1, but illustrating a somewhat modified form of the novel girdle; and Figure 4 is a detail fragmentary vertical longitudinal section of one of the terminal portions of said modified form of girdle, taken on line 4-4 in said Figure 3, and drawn on an enlarged scale.

Similar characters of reference are employed in all of the hereinabove described views, to indicate corresponding parts.

Referring now to said drawings, the reference character 5 indicates the main body of the novel girdle structure, the same being made of any suitable flexible material to permit of its being wound around the waist of the wearer. The design and material of which said main body of the girdle may be made, may also be subject to a wide range of variation as to structural arrangement and ornamental treatment and embellishment, the single requirement being that it is of sufficient flexibility to permit of its being turned about the waist of the wearer. Connected with the respective ends of said main body 5 of the girdle are pendant end members or terminal portions 6. The said pendant end members or terminal portions 6 may be made of any desired material and in any suitable shape, and the same may be provided with such ornamental embellishment as may provide, in combination with the shape, a desirable and attractive appearance and finish. Said pendant end members or terminal portions 6, comprise a front wall or side portion 7 and rear wall or side portion 8, which are joined together at their side and bottom marginal edges, so as to provide, intermediate the same, a pocket or receptacle space 9, the upper portions of said members 7 and 8 being disconnected or separated to provide a mouth or opening 10 giving access to the interior of the pocket or receptacle space 9. As shown in Figures 1 and 2, said pendant end members or terminal portions 6 may be made as separate or independent elements, suitably connected to the extremities of the main body 5 by interconnecting suspension loops or suspension members, such as the cord loops 11 as shown.

It will be apparent that the girdle when worn, may be so arranged that the main body 5 will encircle the waist of the wearer, the free end portions being knotted, as at 12, or otherwise fastened to secure the same

against displacement, said free end portions being at the same time thus held in depending relation to the waist-encircling portion of the main body so as to suspend the pendant end members or terminal portions 6 in front of the wearer, whereby not only do said end members or terminal portions 6 provide a desirable finish to and ornamental embellishment of the girdle, but the same also are conveniently placed so that the utility of the pocket or receptacle space 9 may be readily availed of by the wearer for the carrying of such small articles as handkerchiefs, keys, toilet articles and the like.

Referring now to Figures 3 and 4 of the drawings I have shown a somewhat modified construction of the novel girdle, to illustrate how the same may be varied in structure, arrangement and ornamental effect, while yet retaining all the utility which the same is adapted to provide. In this construction the girdle comprises a flexible main body 13 in strap or band like form, which may be made of any desired fabric material in suitable colors, and possessing suitable figured design. Said main body 13 terminates, at its respective ends, in widened out, preferably integral, pendant end members or terminal portions 14 upon the faces of which are secured an outer section or facing member 15, attached by its side and bottom edges to the corresponding edges of said end members or terminal portions 14 to provide an intermediate pocket or receptacle space 16. The upper end edge of said facing members 15 being disconnected or separated from the end members or terminal portions so as to provide a mouth or opening 17 giving access to the interior of the pocket or receptacle space 16. The end portions thus provided may be furnished with ornamental embellishment, such, e. g., as the edging 18 and tassels 19 if desired. It will be clear that the manner of arranging the above described construction of girdle about the waist of the wearer, with its free end portions having the end members suspended therefrom conveniently in front of the wearer, is substantially the same as already mentioned in connection with the first described construction of girdle.

It will be clearly understood that the girdle, with the novel combined ornamental pendant end members having the useful pockets or receptacle spaces, not only provide a very attractive ornamental finish for the girdle terminations, but by reason of the pocket or receptacle space provided thereby, also afford a very convenient utility to the wearer.

I am aware that, so far as form, material, shape, character of embellishment, and the like are concerned, many widely varying styles and appearances of the novel girdle

may be obtained, without departing from the scope of this invention as set forth in the foregoing specification, and as defined in the appended claims. Hence, I do not limit my invention to the exact arrangements and combinations of the devices and parts making up the girdle as set forth in the foregoing specification, nor do I confine myself to the exact details of the construction of said devices and parts as illustrated in the accompanying drawings.

I claim:

1. An article of wearing apparel in the form of a girdle for exterior wear and adornment, consisting of a flexible main body portion adapted for tying about the waist of the wearer so as to provide pendant free ends, and ornamental terminal portions provided with means forming pocket spaces therein, said terminal portions being attached to said pendant free ends of said main body portion so as to hang therefrom.

2. An article of wearing apparel in the form of a girdle for exterior wear and adornment, consisting of a flexible main body portion adapted for tying about the waist of the wearer so as to provide pendant free ends, ornamental terminal portions attached to said pendant free ends of said main body portion so as to hang therefrom, and said terminal portions having front and rear wall portions interconnected at their side and bottom edges to provide intermediate the same a pocket space having an open mouth at its upper end.

3. An article of wearing apparel in the form of a girdle for exterior wear and adornment, comprising a flexible main body portion adapted for tying about the waist of the wearer so as to provide at least one pendant free end, an ornamental terminal portion attached to said free pendant end to hang therefrom, and means connected with said terminal portion providing a pocket space therein.

4. An article of wearing apparel in the form of a girdle for exterior wear and adornment, comprising a flexible main body adapted for tying about the waist of the wearer so as to provide at least one pendant free end, an ornamental terminal portion attached to said free pendant end to hang therefrom, and said ornamental terminal portion having a front and rear wall portion interconnected at their side and bottom edges to provide intermediate the same a pocket space having an open mouth at its upper end.

In testimony that I claim the invention set forth above I have hereunto set my hand this 6th day of March, 1922.

OTTO DAVID.
